US0D1094021S

(12) **United States Design Patent** (10) Patent No.: **US D1,094,021 S**
(45) Date of Patent: ** Sep. 23, 2025

(54) **BREAST MILK COOLER**

(71) Applicant: **Shenzhen Lute Jiacheng Supply Chain Management Co., Ltd.**, Shenzhen (CN)

(72) Inventor: **Yang Yang**, Shenzhen (CN)

(73) Assignee: **Shenzhen Lute Jiacheng Supply Chain Management Co., Ltd.**, Shenzhen (CN)

(**) Term: **15 Years**

(21) Appl. No.: **29/925,693**

(22) Filed: **Jan. 25, 2024**

(51) LOC (15) Cl. **07-10**

(52) U.S. Cl. **D7/605**

(58) **Field of Classification Search**

(57) **CLAIM**

The ornamental design for a breast milk cooler, as shown and described.

DESCRIPTION

FIG. 1 is a top, front and right side perspective view of a breast milk cooler, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear and left side perspective view thereof.

The broken lines in the drawings show the portion of the breast milk cooler that form no part of the claimed design.

1 Claim, 8 Drawing Sheets
